UNITED STATES PATENT OFFICE.

CHARLES W. KECKLER, OF NEWARK, NEW JERSEY, ASSIGNOR TO WESTERN ELECTRIC COMPANY, INCORPORATED, OF NEW YORK, N. Y., A CORPORATION OF NEW YORK.

TELEPHONE SYSTEM.

1,335,739.

Specification of Letters Patent.

Patented Apr. 6, 1920.

Application filed October 2, 1917. Serial No. 194,304.

To all whom it may concern:

Be it known that I, CHARLES W. KECKLER, a citizen of the United States, residing at Newark, in the county of Essex and State 5 of New Jersey, have invented certain new and useful Improvements in Telephone Systems, of which the following is a full, clear, concise, and exact description.

This invention relates to telephone systems, and more particularly to intercommunicating telephone systems provided with a trunk circuit extending to a central office and multiplied to each of the stations included in the intercommunicating system.

15 The object of this invention is to provide improved holding means for the trunk circuit by means of which electrical continuity of the trunk circuit may be maintained while the original answering station of the 20 system is communicating with another station thereof, thereby to prevent the actuation of the disconnect signal at the central office end of the trunk circuit.

In accordance with this invention, there 25 is provided a bridge which includes a relay winding for holding the trunk circuit in substitution of a telephone set and means for substituting the bridge comprising a locally energized relay which when energized is locked up under control of the bridged relay.

For a more complete understanding of this invention reference should be had to the following description considered in connection with the accompanying drawing containing one embodiment of the invention.

In the drawing there is shown a trunk circuit comprising conductors 5 and 6, which extend to a central office, not shown. This 40 trunk circuit is multiplied to the various stations comprising the system, only two of which, A and B, are shown in the drawing. Each station of the system is provided with the usual telephone set, a trunk answering 45 key T for connecting the telephone set with the trunk circuit, a local answering key L for connecting the telephone set with conductors of the interconnecting system individual to the particular answering station, 50 and with the usual keys (1 and 2 being shown at stations B and A respectively), which are individual to the other stations of the system and which are employed for connecting the telephone set of a calling station 55 with the conductors individual to any called

station of the system. Each of these individual keys is provided with a third contact 12 engaged when the key is depressed to its way-down position for closing a circuit through the signaling device at the called 60 station corresponding to the individual key depressed or actuated. Likewise each of the trunk answering keys T is provided with a third contact 13, the purpose of which will more clearly hereinafter appear, closed only 65 when the trunk answering key is fully depressed to its way-down position. Each of the individual keys and the trunk and local answering keys T and L are of the locking type, so that when depressed it is locked in 70 depressed position by a spring pressed latch plate 7. When locked in depressed position, the extreme right-hand or third contact 12 of the individual key is not closed, while the other two are closed to connect the telephone set with the conductors individual to the called station. When a trunk answering key T is locked in depressed position, the contacts connecting the telephone to the trunk circuit are closed, but contact 13 is 80 open. If one of the keys—either trunk or local answering or individual—is locked in depressed position when a second key at the same station is depressed, the first key will thereby be released and restored to normal 85 position. Each station is also provided with a trunk holding key H which, when actuated, causes the energization of a relay 8 which closes a bridge 9, 10 across the trunk circuit. This bridge includes a relay 11 90 which, when the bridge is closed, is energized to complete a locking circuit for relay 8. Relay 8 may be released by the subsequent actuation of any trunk answering key T which, in closing its way-down right-hand 95 contact, short circuits the winding of relay 8, causing the deenergization thereof.

Referring now to the operation of the system shown in the drawing, it will be assumed that the operator at the central office 100 (not shown) has made connection between the cord circuit thereat and the central office end of the trunk circuit and has projected ringing current out over the trunk circuit to cause the operation of a call bell 15, which 105 in the system illustrated in the drawing, is shown associated with station A of the intercommunicating system. This station A may therefore serve as an answering station 110 of the intercommunicating system as far as

incoming calls over the trunk circuit are concerned. The attendant at station A, in response to the operation of the call bell 15, depresses the trunk answering key T and removes the receiver from the switchhook, thereby connecting the telephone set of station A across the trunk circuit conductors 5 and 6 through contacts 16 and 17 of the trunk answering key T and normal contact 5 of relay 8. If the incoming call is for a party at station B, the attendant at station A momentarily depresses the transfer or holding key H of station A and then depresses the individual key 2 to its way-down position and releases this key which moves into locking position. The momentary depression of the holding key H causes the energization of relay 8 over a circuit from one side of talking battery TB through resistance 18, the winding of relay 8, contact 19 of key H, conductor 20, and through ringing battery RB back to the other side of the talking battery TB. Relay 8, on being energized, closes its alternate contact and opens its normal contact, thereby disconnecting the telephone set from across the trunk circuit and connecting the bridge 9, 10, which includes the winding of relay 11, across the trunk circuit. The holding bridge is thereby substituted for the telephone set. Upon being connected across the trunk circuit relay 11 is energized by current from the central office battery and upon being energized attracts its armature, closing its contact to establish a locking circuit for relay 8. This locking circuit may be traced from one side of the talking battery TB through resistance 18, winding of relay 8, contact of relay 11, conductor 21 through the battery RB to the other side of the talking battery TB. As the individual key 2 is depressed, the plate 7 is actuated to release the trunk answering key T, opening contacts 16 and 17 and preventing the connection of the telephone set of station A with the trunk circuit when the telephone set of station B is subsequently connected therewith. By the closure of contacts 32 and 34 of key 2 upon the depression thereof, the telephone set of station A is connected with the conductors 30 and 35 which are individual to the station B. The depression of the individual key 2 to its way-down position causes the operation of the signaling device 25 at station B. The operating circuit for this signaling device may be traced from one side of the ringing battery RB through conductors 26 and 27, switchhook contact 28, contact and winding of signaling device 25, conductors 29, 30 and 31, contacts 32 and 12 of the key 2, and conductors 33, 20 and 34, back to the other side of the ringing battery RB. Key 2, after being depressed to its way-down position to cause the operation of the signaling device at sta-

tion B, is then released and is locked in depressed position with its contacts 32 and 34 closed and contact 12 open.

The party at station B, in response to the operation of the signaling device 25, depresses the local answering key L and removes the receiver from the switchhook, thereby connecting the telephone set at station B with the individual conductors 30 and 35 through contacts 40 and 41 of the local answering key L of station B. The attendant at station A may now inform the party at station B that there is a trunk call for the party B, whereupon the attendant at station A may restore the receiver to the switchhook. The party at B may then actuate (depress) the trunk answering key T, thereby releasing the local answering key L, which disconnects the telephone set of station B from the conductors 30, 35 and connects this telephone set with the trunk circuit through contacts 16 and 17 of the trunk answering key T of station B. The trunk key in being depressed is fully depressed to its way-down position, to de-energize relay 8 by establishing a short circuit about this relay. This short circuit may be traced from the upper terminal of resistance 18 through conductors 42 and 43, contact 13 of the trunk answering key T of station B, conductors 44, 45 and 34, to a terminal of the ringing battery RB. The relay 8 thereupon releases its armature, opening its alternate and closing its normal contact. The opening of its alternate contact opens the bridge and disconnects the winding of relay 11 from the trunk circuit. Relay 11 thereupon releases, opening its contact which is in the locking circuit of relay 8. The trunk answering key T of station B, after being depressed to its way-down position, may then be released, whereupon it is locked in its depressed position, with its contacts 16 and 17 closed and its contact 13 open. At the conclusion of the conversation the party at station B restores the receiver to the switchhook, thereby permitting the release of the supervisory relay of the cord circuit at the central office whereupon a disconnect signal is given to the operator thereat.

It is to be noted that this invention provides very simple means for holding the trunk circuit in substitution for the telephone set of an intercommunicating system, and in so doing utilizes a very small amount of apparatus which is common to the trunk circuit and permits the use of keys at the various stations of the intercommunicating system which are of very simple construction.

What is claimed is:

1. In a telephone system in combination, a plurality of subscribers' stations, a trunk circuit multiplied to the stations, a telephone

set at each station adapted to be connected with the trunk circuit, a bridge including a relay for holding the trunk circuit in substitution of a telephone set, switching means including a relay energized over a circuit independent of the telephone sets controlling such substitution, a locking circuit for the second relay established upon the energization of the bridged relay, a switching device for connecting a telephone set with the trunk circuit, and a disabling circuit for the second relay established upon the actuation of the switching device.

2. In a telephone system, in combination, a plurality of subscribers' stations, a trunk circuit multiplied to the stations, a telephone set at each station, a trunk key at each station having contacts controlling the connection of the telephone set thereat with the trunk circuit, one of the telephone sets being connected with the trunk circuit, a holding key at each station, a bridge comprising a relay winding for maintaining the circuit continuity of the trunk circuit in substitution of a telephone set, a relay energized upon the actuation of a holding key over a circuit independent of the telephone sets to

connect the bridge across the trunk circuit, and to disconnect the engaged telephone set from the trunk circuit, and a locking circuit 30 for the second relay completed through a contact of the bridged relay upon the energization thereof.

3. In a telephone system, in combination, a plurality of subscribers' stations, a trunk 35 circuit multiplied to the stations, a telephone set at each station, a trunk key at each station having contacts controlling the connection of the telephone set thereat with the trunk circuit, a holding key at each station, 40 a bridge comprising a relay winding for maintaining the circuit continuity of the trunk circuit in substitution of a telephone set, a relay energized upon the actuation of a holding key over a circuit independent 45 of the telephone sets to connect the bridge across the trunk circuit, and a disabling circuit for the second relay established upon the subsequent actuation of a trunk key.

In witness whereof I hereunto subscribe 50 may name this 29th day of September, A. D. 1917.

CHARLES W. KECKLER.
